UNITED STATES PATENT OFFICE.

SAMUEL HAWKES, OF CORNING, NEW YORK.

DESIGN FOR A GLASS PITCHER.

40,324.

Specification for Design.

Patented Nov. 2, 1909.

Application filed June 26, 1909. Serial No. 504,624. Term of patent 7 years.

To all whom it may concern:

Be it known that I, SAMUEL HAWKES, a citizen of the United States, residing at Corning, in the county of Steuben and State of New York, have invented a new, original, and ornamental Design for a Glass Pitcher, of which the following is a specification, reference being had to the accompanying drawing, forming part thereof.

Figure 1 is a front elevation of a glass

pitcher showing my new design. Fig. 2 is a side elevation of the same.

I claim,

The ornamental design for a glass pitcher, as shown.

SAMUEL HAWKES.
